CLAIM

The ornamental design for a floor mat, as shown and described.

DESCRIPTION

FIG. 1 is a perspective view of a floor mat, showing my new design;

FIG. 2 is a front elevation view thereof;

FIG. 3 is a rear elevation view thereof;

FIG. 4 is a left side elevation view thereof; the right side elevation view being the same;

FIG. 5 is a top plan view thereof; and,

FIG. 6 is a bottom plan view thereof.
